UNITED STATES PATENT OFFICE.

LUKE EMILIE BESSETTE, OF BANFF, ALBERTA, CANADA, ASSIGNOR OF ONE-HALF TO
LOUIS SIDNEY CROSBY, OF BANFF, ALBERTA, CANADA.

EXTENSION TABLE.

Application filed April 11, 1922. Serial No. 551,602.

To all whom it may concern:

Be it known that I, LUKE EMILIE BESSETTE, a subject of the King of Great Britain, and resident of Banff, in the Province of Alberta and Dominion of Canada, have invented certain new and useful Improvements in Extension Tables, of which the following is a specification.

This invention relates to improvements in extension tables, and has for its objects to provide means whereby a circular table may be provided within its flange with a resilient metallic strip rigidly carried by the leg support of the table and designed to slide within supporting members carried by the table.

Further objects are to provide a means whereby the extension pieces of the table may be suitably secured thereto; to provide a means of locking the two portions of the table together when the extension pieces are not used.

Still further objects are to provide a means whereby the two portions of the table are prevented from coming altogether separated, and this means consists of a draw bar carrying pulleys which are engaged by flexible elements anchored to the two portions of the table.

A still further object is to provide an extension table that is simple in construction, not liable to go out of repair, and generally to adapt the several parts to better perform the functions required of them.

And the invention consists essentially of the improved construction and arrangements of parts, hereinafter described in detail in the accompanying specification and drawings.

In the drawings:

Figure 1 is a side elevation of the improved extension table.

Figure 2 is a side elevation of the same, showing one of the extension pieces in position.

Figure 3 is a side view, showing the table and extension piece partly in elevation and partly in section.

Figure 4 is a bottom plan view of the improved table with the leg support cut off.

Figure 5 is a side view of the table, partly in section and partly in elevation, and taken at right angles to the view shown in Figure 1.

Figure 6 is a perspective view of one of the extension pieces or boards.

Figure 7 is a sectional detail on the line 7—7, Figure 4.

Figure 8 is a perspective detail of one of the supporting members for the metallic strip.

Figure 9 is a perspective view of one of the locking members.

Figure 10 is a perspective view of the draw bar.

In the drawings, like characters of reference indicate corresponding parts in all the figures.

Referring to the drawings:

A represents the improved table which is made according to well-known construction, but preferably circular in shape. The table A comprises a top 10 which is formed of two semi-circular portions 11 and 12 provided with the usual annular flange 13 which is also made of two sections, each fastened to one of the semi-circular members 11 and 12.

Fastened on the inner face of the annular flange 13 are a plurality of hangers or supporting members 14 which are L-shaped in form and provided with fingers 15 and 16 which are designed for a purpose that will be hereinafter made clear. The supporting members 14 are secured to the top sections 11 and 12 of the table by suitable fastening means extending through the orifices 17 provided in one of the arms of the L-shaped supports.

The table is provided with a supporting leg 18 which is formed with the usual standard 19 mounted on the foot 20. The standard 19 is provided at its upper end with a board 21 extending transversely of the table and secured to the standard 19 by means of a squared extension 22 extending in a recess provided on the top part of the standard. The board 21 is provided at either end with brackets 23 and 24 suitably secured thereto at 25 and each being securely fastened as at 26 intermediate of the length of two flexible metallic strips 27 and 28.

The metallic strips 27 and 28 are designed to slidably extend within the fingers 15 and 16 of the supporting members 14 carried by the table sections 11 and 12 adjacent to the annular flange 13. Obviously, by means of this arrangement, when the two sections 11 and 12 of the table are pulled apart, the leg support 18 will remain stationary, and the free ends of the two metallic strips 27 and 28 sliding within the supporting mem-

bers 14 will bear against the inner face of the annular flange 13 and thus be permanently tight against the same.

The two metallic strips 27 and 28 being normally straight, are forced to assume a semi-circular form when in engagement with the fingers of the supporting members 14 by the annular flange 13 against which the two strips are in bearing engagement.

10 The board 21 supports a draw bar 29 which extends at right angles thereto intermediate of its length and is formed in its inner face with a longitudinal groove 30 designed to slidably engage ribs 31 and 32 provided on the underface of the two table sections 11 and 12, respectively. Further, the underface of the portions 11 and 12 of the table are each provided with a pair of rails 33 and 34, each of which extend adjacent to and 15 parallel with the ribs 31 and 32 and are designed to engage the upper or flanged edge of the draw bar 29 formed by the longitudinal groove 30. This arrangement strengthens the table and prevents the two portions 20 11 and 12 from deviating laterally when the same are drawn apart.

The ends of the draw bar 29 are formed with notches 35 and 36 in which are mounted two pulleys 37 and 38. The pulley 37 is 25 engaged by a flexible element 39 which has one of its extremities anchored as at 40 to one of the rails 33 provided on the underface of the table portion 11, while the other extremity of the flexible element 39 is anchored 30 as at 41 to the rail 34 provided on the table section 12.

The pulley 38 is also engaged by a flexible element 42 which has one of its extremities secured to the table section 11 at 40 while 35 its remote extremity is anchored at 41 on the table section 12. This obviously will limit the outward sliding movement of the two portions of the table, and will prevent the same from becoming disengaged.

40 The gap formed when the two sections 11 and 12 are drawn apart, is designed to be bridged by a series of extension pieces or boards 43 which are each formed intermediate of their length on its lower face with a 45 transverse rib 44 designed to engage the groove 30 of the draw bar 29, which will securely retain the boards 43 in position. These boards will be prevented from tilting as their outer ends will be supported by the metallic strips 27 and 28.

When the extension pieces 43 are not used, the two sections 11 and 12 of the table are forced together, and may be locked in this position by means of locking members 45 and 46 located at either side of the section 50 11 of the table and designed to engage with slots 47 formed in the flange 13 of the portion 12 of the table adjacent to the top 10 thereof.

When this table is in use and it is desired to 55 extend the same so as to provide a longer

table, the portions 11 and 12 are drawn apart, the leg support 18 remaining stationary. The sections 11 and 12 will slide on the metallic strips 27 and 28 which will extend through the supporting members 14 and, in this action, the intermediate portions of the two metallic strips 27 and 28 will be held in straight position, while the outer ends thereof will be curved in their engagement through the members 14 with the annular flange 13 of the table sections. The outer ends of the metallic strips thus being held in tight engagement with the annular flange 13, the two sections of the table will be firmly held in position.

A further means of securing the table sections in position and preventing the same from any lateral movement is provided by the arrangement of the grooved draw bar which is in engagement with the ribs 31 and 32 and the rails 33 and 34 provided on the two sections of the table; also the arrangement of the flexible elements 39 and 42 with the pulleys 37 and 38 will limit the outward movement of the sections 11 and 12 of the table and prevent the two sections from becoming disengaged from the draw bar 29.

When the sections 11 and 12 have been pulled apart, the required number of extension boards 43 are filled in, the rib 44 thereof being engaged by the revealed portion of the groove 30, while the outer ends of the boards will be supported by the straight part of the strips 27 and 28.

When a large table is not needed, the extension boards 43 are removed and the portions 11 and 12 of the table being brought together in engagement and locked in this position by means of the locking members 45 and 46 being brought into engagement with the slots 47 provided on the flange of the table. If desired and to prevent the free ends of the metallic strips 27 and 28 from catching on the inner surface of the annular flange 13, the said outer ends may 100 be deflected to a slight degree as shown at 48 in Figure 4 of the drawings.

As many changes could be made in the above construction and many apparently widely different embodiments of my invention within the scope of the claims, constructed without departing from the spirit or scope thereof, it is intended that all matter contained in the accompanying specification and drawings shall be interpreted as illustrative and not in a limiting sense.

What I claim as my invention is:

1. An extension table comprising a circular top and an annular flange, the top and flange being formed of two semi-circular sections, a leg support for the table, metallic strips slidably located on the inner side of the annular flange, means to support the metallic strips and retain them in close engagement with the flange, angle braces se- 120

125 130

5 curing the strips intermediate of their length to the leg support, a draw bar carried by the leg support provided with a longitudinal groove, extension pieces for the table, and a rib extending across each extension piece designed to engage the groove, as and for the purpose described.

10 2. An extension table comprising a circular top and an annular flange, the top and flange being formed of two semi-circular sections, a leg support for the table, metallic strips slidably located on the inner side of the annular flange, means to support the metallic strips and retain them in close engagement with the flange, angle braces securing the strips intermediate of their length to the leg support, a draw bar carried by the leg support provided with a longitudinal groove designed to be in sliding engagement

15 20 with ribs carried by the top sections, extension pieces for the table, and a rib extending across each extension piece designed to engage the groove, as and for the purpose described.

3. An extension table comprising a circular top and an annular flange, the top and flange being formed of two semi-circular sections, a leg support for the table, metallic strips slidably located on the inner side of the annular flange, means to support the metallic strips and retain them in close engagement with the flange, angle braces securing the strips intermediate of their length to the leg support, a draw bar carried by the leg support provided with a longitudinal groove designed to be in sliding engagement with ribs carried by the top sections, extension pieces for the table, a rib extending across each extension piece designed to engage the groove, and means on the draw bar to limit the outward sliding movement of the table.

In witness whereof I have hereunto set my hand in the presence of two witnesses.

LUKE EMILIE BESSETTE.
